UNITED STATES PATENT OFFICE.

ADAM HEUNISCH, OF SAN FRANCISCO, CALIFORNIA.

DESIGN FOR A BOTTLE-STOPPER ATTACHMENT.

SPECIFICATION forming part of Design No. 35,499, dated December 31, 1901.

Application filed November 22, 1901. Serial No. 83,350. Term of patent 7 years.

To all whom it may concern:

Be it known that I, ADAM HEUNISCH, a citizen of the United States, residing in the city and county of San Francisco, State of California, have invented and produced a new and original Design for a Bottle-Stopper Attachment, of which the following is a specification, reference being had to the accompanying drawings, forming part thereof.

Figure 1 is an elevation of my design. Fig. 2 is a vertical section.

My design is particularly applicable for caps or cups which are adapted to be secured to the necks of bottles and inclose the stopple. Its material feature resides in a cup of two approximately cylindrical or slightly-tapered sections A and B of different diameters united near the horizontal transverse center of the cup by a short inclined or beveled intermediate section C, converging from the top of the larger section A to the bottom of the

smaller section B, and in conjunction therewith of inclined and oppositely-located depressions D on the outside of the cup above the bottom edge, which form elevations or protuberances E on the inside thereof at opposite points. The bottom edge of the section A is provided with an annular flange F. The closed end of the smaller section B is slightly convex and unites with the cylindrical portion by a continuous curve, as shown.

Having described my invention, what I claim as new, and desire to secure by Letters Patent, is—

The design for a bottle-stopper attachment as herein shown and described.

In witness whereof I have hereunto set my hand.

ADAM HEUNISCH.
